Primary Examiner — Robert M. Spear*Assistant Examiner* — Kendra Leslie Hamilton(74) Attorney, Agent, or Firm — CK IP Law(57) CLAIM

We claim the ornamental design for a beverage consumption straw, as shown and described.

DESCRIPTION

FIG. 1 is a top left side perspective view of a beverage consumption straw, showing our new design;

FIG. 2 is a front elevational view thereof;

FIG. 3 is a bottom right side perspective view thereof;

FIG. 4 is a rear elevational view thereof; and,

FIG. 5 is a left side cross-sectional elevational view thereof, taken in the direction of line 5-5' of FIG. 4.
